AUTOMOBILE HEADLIGHT LENS

Filed March 5, 1930

Fig. 3.

INVENTOR
Maurice A. Smith,
By Archworth Martin,
Attorney.

UNITED STATES PATENT OFFICE

MAURICE A. SMITH, OF JEANNETTE, PENNSYLVANIA, ASSIGNOR TO MCKEE GLASS COMPANY, OF JEANNETTE, PENNSYLVANIA, A CORPORATION OF PENNSYLVANIA

DESIGN FOR AN AUTOMOBILE HEADLIGHT LENS

Application filed March 5, 1930. Serial No. 34,734. Term of patent 14 years.

To all whom it may concern:

Be it known that I, MAURICE A. SMITH, a citizen of the United States, residing at Jeannette, in the county of Westmoreland, State of Pennsylvania, have invented a new, original, and ornamental Design for Automobile Headlight Lenses, of which the following is a specification, reference being had to the accompanying drawings, forming a headlight lens as shown.

Figure 1 is a rear elevational view of a lens embodying my new design;

Fig. 2 is a sectional view, taken on the line 2—2 of Fig. 1, and

Fig. 3 is a sectional view, taken on the line 3—3 of Fig. 1.

I claim:

The ornamental design for an automobile headlight lens as shown.

MAURICE A. SMITH
